Lawrence Brin Fox.

United States Patent Office.

LAWRENCE B. FOX, OF WILLIAMSPORT, PENNSYLVANIA.

Letters Patent No. 77,025, dated April 21, 1868; antedated April 7, 1868.

IMPROVED METHOD OF FINISHING LEATHER.

The Schedule referred to in these Letters Patent and making part of the same.

TO ALL WHOM IT MAY CONCERN:

Be it known that I, LAWRENCE B. FOX, of the city of Williamsport, county of Lycoming, and State of Pennsylvania, have invented a new and improved Method of Finishing Leather; and I do hereby declare that the following is a full and exact description thereof, reference being had to the accompanying drawings, and to the letters of reference marked thereon.

The nature of my invention consists in providing a movable table upon which the hide can be placed and managed by the operator during the finishing-process, and also the peculiar construction and combination of a proper plane-stock, all used by the aid of steam or other power, saving much manual labor, and making a better article at a reduced price, as will be readily seen by definite description of my machine.

To enable others skilled in the art to make and use my invention, I will now proceed to describe its construction and operation.

Upon a proper frame, as shown in Figure 1, I put a convenient track, H, on which the table-legs provided with slots to fit said track can move laterally, which legs are designated by A. The top of the table B is round, and provided with arms b b, which arms or braces are fastened to a sleeve or thimble, c', by means of which thimbles c' c'', the table can be easily rotated on the shaft C. Beneath the thimble c' I attach two rings, d d, to which I fasten the cord e, and pass the same over the pulleys f f, Figure 2, to which pulleys is fixed a crank, g, which is operated by hand, but which can as well be operated by the steam or other power by means of a loose pulley.

i i is an ordinary framework to support the necessary machinery I use, and to which, at its upper part, is fixed the band-wheel J, from which I take the driving-power. To this wheel I fasten the wrist K and shaft L, which shaft, by means of another wrist M, is attached to the plane-stock N, which stock is provided with a groove, R, which runs in the frame n. In the plane-stock N are put two sleeks O O, as shown in Figures 1, 2, 3, and 4, and held by means of set-screws p p. To one end of the plane-stock I fasten suitable ears, 1, 2, 3, 4, shown in fig. 4, by which means the standard 5 and the band and bevel-gear wheel 6 are secured. The Level-gear is the same as that in ordinary use for similar purposes, and therefore does not need further description. On the lower part of the standard 5, I place a circular knife, 7, and on the bevel-wheel 6, I have an indentation, shown at 8, in which a cord is retained, and the cord 9. An endless belt passes over a similar drum attached to the wrist K, and marked K'. To the frame n is fastened the standard r, which runs in the slides s, and adjusted by the set-screw t, by means of which the plane-stock can be at once raised or lowered, as demanded, while the machine is in motion.

It will be seen that the plane-stock can be removed with ease, and a rubber of stone, wood, or iron, used in its place for the purpose of polishing the surface, if required. It will be also seen that the leather placed upon the table B, can, by means of the rotary and lateral motion, be brought at all points in contact with the cutting-surfaces of the sleeks O O, and the circular knife 7, saving a large amount of manual labor, and at the same time making a perfect because uniform finish, from the fact that the said cutting-surfaces maintain an unchanged position, the pressure being constantly the same.

Having thus described my invention, what I claim, and desire to procure by Letters Patent, is—

1. The plane-stock for finishing leather, with its two sleeks and circular knife, as described and shown.
2. In combination with the plane-stock, as described, I claim the adjustable table, constructed and operated as shown, and for the purposes set forth.
3. I claim the combination and arrangement of the several parts composing my finisher when used for the purposes already stated.

L. B. FOX.
